PHOTOGRAPHIC REPRODUCTION PROCESS, INCLUDING TRANSFER OF AZO DYES

Anthony Marriage, Felix Pollak, and Philip K. Brooks,
Harrow, England, assignors to Eastman Kodak Company,
Rochester, N. Y., a corporation of New Jersey

Application March 31, 1953, Serial No. 345,798

4 Claims. (Cl. 101—149.1)

This invention relates to photographic reproduction processes.

In the field of color photography, the production of dye images by the so-called silver-dye-bleach process is well known. In this process, a silver image in a photographic layer containing a dyestuff uniformly dispersed therein is bleached by treatment with a suitable bleaching agent whereby the dyestuff is destroyed in the layer at the places where silver is present. The dyestuff is then left in the layer as a positive dye image complementary to the negative silver image. The dyestuffs which have been proposed for this process are chiefly azo dyes.

We have found that dye from a dye image so formed in a single photographic layer may be transferred onto an absorbent support to form a dye image thereon; provided of course the dye is one which will diffuse or can be made to diffuse.

According to the present invention, therefore, there is provided a method of photographic reproduction in which a photographic emulsion layer containing a silver image preferably a two-tone image such as a line or halftone image, or a continuous tone silver image, is treated with a silver dye bleach bath in the presence of a dye capable of being bleached in the presence of metallic silver to form a positive dye image in the layer, preferably a diffusible acid azo dye, and is then brought into contact with a receiving absorbent support whereby part or all of the dye is transferred so as to form a positive dye image in the absorbent support.

It is apparent that the transferred image will be laterally reversed with respect to the dye image first formed in the emulsion layer.

When performing the invention, a light-sensitive silver halide emulsion layer is exposed to an object or image and then developed to form the said silver image.

The image dye may be introduced into the layer at any one of various stages; thus, it may be incorporated in the emulsion before coating or the layer may take up dye from the developer, from a separate bath or from the bleach bath.

The production of several copies from a layer containing a positive dye image formed as described above can be effected by transferring only a part of the dye forming the dye image in the emulsion layer. The proportion transferred depends on several factors including the time of contact of the layer and the support.

This time of contact must be long enough to allow the transfer of sufficient dye to form a clear image on the support.

Any of the known silver dye bleach baths are suitable for use in the present invention such as acid thiourea solutions. If desired, a compound such as anthraquinone-2-sulfonic acid or 2,3-dimethyl quinoxaline may be used with the bleaching agent to accelerate the bleaching action, as is also well-known in the art.

The time of transfer of sufficient dye to form a clear copy image can usually be reduced by treating the support

2

before transfer with water or preferably dilute alkali, e. g. a solution of sodium carbonate or ammonia. This treatment appears to facilitate the transfer of the dye.

If it is desired to obtain as many copies as possible from a single exposure of the photographic emulsion, it is preferable to use a high contrast emulsion, by which term we mean an emulsion which produces a large change in the amount of silver for a given change in the logarithm of the exposure, and not necessarily one which produces

10 a high visual density.

Using such an emulsion, it is possible to obtain several copies from the first dyeing of the emulsion layer, and then, when the dye in this layer has been partially or completely exhausted, to redye and rebleach the layer after which further copies may be obtained from the fresh positive dye image in the layer. This procedure of transferring a number of copies, redyeing, and rebleaching may be repeated as long as enough silver is present to bleach dye sufficiently to form a clear image when transferred.

The invention is particularly applicable to document copying and a number of copies of an original document may be made as described above without having to make more than one photographic exposure. This is in distinction to most prior document copying processes in which one copy only is obtained from a single photographic exposure step. For example, if a photographic negative of a document has been made by the reflex method, this negative can be used to make several positive copies of the document by application of our invention without any further photographic exposure step.

Thus, there may be taken a photographic emulsion layer containing a laterally reversed negative silver image of a document taken by the reflex method. The following treatments can then be performed in the light provided that either the image has been fixed or the first of the treatments inhibits further development. The negative is treated in a bath of a dye bleachable in the presence of silver so that the dye is uniformly distributed in the emulsion. It is then treated with a suitable silver dye bleaching agent, e. g. acid thiourea solution, so that the dye is bleached where it is in contact with metallic silver. A positive dye image is thereby formed in the emulsion layer. The emulsion layer containing the positive dye image is then brought into contact with a receiving absorbent support such as a paper support, whereby dye from the positive image is transferred to the support to form the laterally reversed dye image. The support is preferably treated with water or dilute alkali just before transfer as stated above.

If the positive dye image first formed in the emulsion layer is laterally reversed relative to the original document, as it would be when formed from a negative taken by reflex, then when dye is transferred to the support the dye image is again laterally reversed and is a laterally correct positive dye image of the original document.

Additional copies are made simply by bringing the already prepared and at least once used negative which still contains dye, into contact with another support so that transference of dye takes place to form another dye image. This procedure according to our invention may be repeated until silver in the negative image is practically exhausted.

The accompanying drawings illustrate in greatly enlarged cross-sectional view the appearance of representative materials at various stages in a process of our invention.

The following examples illustrate but do not limit the application of the process provided by our invention.

Example 1

70 A layer of an unwashed chloro-bromide emulsion, was exposed to a document by reflex, developed for one min-

ute, dyed up in a solution of $\frac{1}{2}\%$ of a diffusible or potentially diffusible acid azo dye such as Chlorazol Fast Pink BK dye (C. I. No. 353) for $2\frac{1}{2}$ minutes, rinsed in water for 5 seconds, bleached by immersing for 30 seconds in an aqueous solution made up of 5 grams of thiourea, .01 gram 2:3-dimethyl quinoxaline and 5 cc. of concentrated hydrochloric acid made up to 100 cc. with water and rinsed for 5 seconds. The dye image thus obtained was then transferred onto an alkaline gelatin coated paper (pretreated for 1 minute in a solution containing 1% ammonia and 0.1% sodium hexametaphosphate) by means of a dye transfer blanket. It was removed after $\frac{1}{2}$ minute and again squeegeed for 1 minute on to fresh, pretreated dye transfer paper. Another transfer was made onto fresh paper, taking 3 minutes.

The process of this example is illustrated in the accompanying drawings wherein Stage 1 shows the developed negative having support 10 and emulsion layer 11 containing the silver image 12 which may be a line, halftone or continuous tone image. After dyeing the element appears as in Stage 2 the emulsion layer now being uniformly colored with the bleachable azo dye. Stage 3 shows the emulsion layer after bleaching the dye in the region of the silver image 12, dye now remaining only in areas 13 of layer 11. In Stage 4 the azo dye is shown transferring by imbibition from areas 13 of the emulsion layer 11 to areas 14 of the hydrophilic surface of the coated paper having support 15 and the gelatin layer 16.

Example 2

A layer of a washed bromide emulsion was coated at the rate of 6.2 grains of gelatin per square foot. This was exposed and processed by the procedure of Example 1. Transfer was made onto gelatin coated paper. Transfer time was 1 minute, and 3 minutes for a second copy.

Example 3

Naphthalene Black dye No. 30745 I. C. I. (an acid azo dye) was used instead of the Chlorazol Fast Pink BK used in Example 1.

Example 4

A sheet of light sensitive material as described in Example 2 was exposed imagewise and treated for 4 minutes with a solution of the following composition

Elon (Metol)	0.1 gram.
Sodium sulfite (anh.)	1.5 gram.
Hydroquinone	0.4 gram.
Sodium carbonate (anh.)	1.7 gram.
Potassium bromide	0.1 gram.
Chlorazol Fast Pink BK dye	4.0 grams.
Water	1 liter.

The material was then rinsed for a few seconds and bleached, rinsed and transferred as in Example 1.

Example 5

A sheet of high contrast photographic paper was exposed to a document by reflex and developed and fixed. The following solution was then applied by swabbing to the surface of the negative.

Concentrated hydrochloric acid	$\frac{1}{2}$ cc.
Thiourea	10 grams.
2:3-dimethylquinoxaline	0.02 gram.
Chlorazol Fast Pink BK dye	0.2 gram.
Water	100 cc.

This solution simultaneously dyed the negative and bleached the dye imagewise. After about 30 seconds swabbing, the dye density in the image areas appeared satisfactory. Excess liquid was squeegeed off the negative and the dye bleaching reaction was allowed another 15 seconds to complete. The negative was then squeegeed without rinsing on to a gelatin coated paper that had been pretreated for 5 minutes with a 1% ammonia solution. After 20 seconds in contact, a dense copy having a clear

background was obtained. The negative still contained dye for further transfers and also still contained silver in the non-image areas for several repetitions of the dye bleaching and transfer procedure.

All operations in these examples were carried out at room temperature (70° F.).

The process of our present invention is also applicable to multicolor photography. Color separation negatives of colored objects are dyed in their respective subtractive colors with dyes capable of being bleached in the presence of silver. Treatment of such dyed negatives with a silver dye bleach bath yields the positive dye images in the emulsions and dyes from these positive dye images are transferred in register onto a single base which may be paper or a transparent base, to form a positive laterally correct image of the original subject. In the same manner that several copies of a document may be made by several transfers, so several positive reproductions of a colored object may be made from the separation negatives.

As stated above the time of transfer of sufficient dye to form a clear copy image can be reduced by treating the support before transfer with water or preferably dilute alkali e. g. a solution of sodium carbonate or ammonia. This treatment appears to facilitate the transfer of dye.

We have also found that the presence of a thiosulfate in or on the receiving support enables the transfer time of the dye from the emulsion layer to the support to be reduced; however the amount of reduction depends on the dye used.

According to an alternative method of the present invention, therefore, there is provided a method of photographic reproduction in which a photographic emulsion layer containing a silver image is treated with a silver dye bleach bath in the presence of a dye capable of being bleached in the presence of metallic silver (such as an acid azo dye) to form a positive dye image in the layer and is then brought into contact with a receiving absorbent support which has been previously treated with a thiosulfate, whereby part or all of the dye is transferred so as to form a positive dye image in the absorbent support.

Preferably, a thiosulfate such as an alkali metal or ammonium thiosulfate is incorporated in the dilute alkali solution used to pretreat the receiving support.

Particularly good results are obtained when using the Naphthalene Black dye given above.

A suitable receiving support comprises a paper base coated with a layer of gelatin.

In a preferred form of this variation of our invention, an emulsion layer containing a positive dye image is brought into contact with a receiving absorbent support, whereby dye from the positive dye image is transferred to the support imagewise, the support having been first treated with a solution of sodium or ammonium thiosulfate made alkaline, for example, with sodium carbonate or ammonia.

Wetting the emulsion layer containing the positive dye image by a dilute carbonate solution further improves the speed of transfer of the dye when taking the first copies.

The following examples illustrate this variation of the present invention.

Example 6

(a) A sheet of high contrast photographic paper was exposed by reflex to a document and developed in a caustic developer.

(b) The negative was dyed for 20 seconds in a solution of 1 gram Naphthalene Black dye in 100 cc. in 25 hydrochloric acid, rinsed, bleached as usual, squeegeed and transferred by means of a mangle onto a paper support which had been wetted by immersing for a few seconds in a bath containing 12.5 grams of $\text{Na}_2\text{S}_2\text{O}_3 \cdot 5\text{H}_2\text{O}$ and 3.2 grams of $\text{Na}_2\text{CO}_3 \cdot \text{H}_2\text{O}$ in 100 cc. of solution. The transfer paper may be an ordinary paper base or a baryta coated paper. Transfer of the dye was allowed to proceed for five seconds. The negative was removed and

again brought into contact for five seconds with freshly conditioned transfer paper. Thirteen transfers in all, each lasting 5-10 seconds, were effected in this manner.

(c) After effecting these transfers, the original negative still contained an appreciable amount of silver. The procedure set out in (b) above was therefore repeated, that is, the negative was redyed and rebleached and by subsequent transfers 14 copies were obtained.

(d) Since silver was still present in the negative, it was again subjected to the procedure according to (b) 10 and 17 copies were obtained.

Thus a total of 44 copies was obtained from one negative.

Example 7

A dye solution of double the acid and dye concentration employed in Example 6 was used. Three dyeings as in Example 6 (b), (c) and (d) of 15, 20 and 3 seconds respectively followed by bleaching and transfer, yielded 12, 16 and 10 copies which were denser than those of Example 6. In this procedure a transfer blanket was used instead of a mangle and the negative was given a short rinse after each bleaching.

Example 8

The dye bleach bath of Example 7 was used. Two dyeings of 30 seconds each as in Example 6 (b) and (c) followed by bleaching and transfer, yielded 7 and 10 dense copies respectively. The transfer time was 20 seconds. The addition of a small amount of optical bleach to the conditioning bath after the 13th transfer gave a noticeably whiter (less yellow) background.

Strong alkalis (4% NH₃ or N/10 NaOH) have similar effects to thiosulfate but replacement of thiosulfate by an equivalent amount of sodium sulfite does not produce the same exceptional change in ease of transfer.

The following acid azo dyes are given as further examples of bleachable azo dyes giving useful results when employed in our invention in the manner of the above examples:

Direct Sky Blue GS 300 (C. I. No. 518)
Acid Brown (Schultz No. 294)
Chlorazol Black, I. C. I.

What we claim is:

1. A photographic reproduction process which comprises uniformly coloring a photographic emulsion layer containing a silver image, with a diffusible acid azo dye, treating the colored emulsion layer with a solution of a silver-dye-bleaching agent until the azo dye in the emulsion layer in the region of the silver image has been decolorized, pressing the emulsion layer into contact with an

alkaline hydrophilic surface containing a compound of the group consisting of alkali metal and ammonium thiosulfates, in the presence of moisture to imagewise transfer a portion of the azo dye image remaining in the emulsion layer to said surface.

5 2. A photographic reproduction process which comprises exposing a light-sensitive silver halide emulsion layer to a subject, developing a silver image in the exposed emulsion layer and uniformly coloring the emulsion layer by means of a silver halide developing solution containing a diffusible acid azo dye, treating the colored emulsion layer with a solution of a silver-dye-bleaching agent until the azo dye in the emulsion layer in the region of the silver image has been decolorized, pressing the emulsion layer into contact with an alkaline hydrophilic surface containing a compound of the group consisting of alkali metal and ammonium thiosulfates in the presence of moisture to imagewise transfer a portion of the azo dye image remaining in the emulsion layer to said surface.

15 3. A photographic reproduction process which comprises uniformly coloring a photographic emulsion layer containing a silver image, with an aqueous solution of a diffusible acid azo dye, treating the colored emulsion layer with a solution of a silver-dye-bleaching agent until the azo dye in the emulsion layer in the region of the silver image has been decolorized, pressing the emulsion layer into contact with an alkaline hydrophilic surface containing a compound of the group consisting of alkali metal and ammonium thiosulfates in the presence of moisture to imagewise transfer a portion of the azo dye image remaining in the emulsion layer to said surface.

20 4. A photographic reproduction process which comprises treating a photographic emulsion layer containing a silver image with an aqueous solution of a mixture of a silver-dye-bleaching agent and a diffusible acid azo dye until the emulsion layer contains an azo dye image only in the region free of the silver image, pressing the emulsion layer into contact with an alkaline hydrophilic surface containing a compound of the group consisting of alkali metal and ammonium thiosulfates in the presence of moisture to imagewise transfer a portion of the azo dye image to said surface.
